UNITED STATES PATENT OFFICE.

JAMES T. LISONBEE, OF FORT DUCHESNE, UTAH, ASSIGNOR TO M. C. LISONBEE, OF MESA, ARIZONA.

TAIL-LIGHT AND NUMBER-PLATE FOR MOTOR-VEHICLES.

1,233,677.

Specification of Letters Patent. Patented July 17, 1917.

Application filed June 29, 1915. Serial No. 37,008.

To all whom it may concern:

Be it known that I, JAMES T. LISONBEE, a citizen of the United States, residing at Fort Duchesne, in the county of Uintah, and State of Utah, have invented certain new and useful Improvements in Tail-Lights and Number-Plates for Motor-Vehicles; and I do hereby declare the following to be a full, clear, and exact description 10 of the invention, such as will enable others skilled in the art to which it appertains to make and use the same.

This invention relates to new and useful improvements in tail lights and number 15 plates for motor vehicles and the like and the principal object of the invention is to provide a combined tail light and number plate which is visible in the day light or after dark.

20 Another object of the invention is to provide an illuminated number plate wherein the numerals are easily distinguishable and may be read without inconvenience.

25 A further object of the invention is to provide a device wherein the number plates are interchangeable so that any number or combination of numbers may be placed in the device thus enabling the same to be used under varying conditions.

30 With these and other objects in view, the invention consists in the novel combination and arrangement of parts which will be fully set forth in the following specification and accompanying drawings, in 35 which:—

Figure 1 is a top plan view of a tail light and number plate constructed in accordance with this invention showing the cover partially broken away to more clearly 40 illustrate the details of construction.

Fig. 2 is a face view of the device, and

Fig. 3 is a transverse sectional view on line 3—3 of Fig. 1.

Referring now to the drawings by characters of reference, the numeral 1 designates as an entirety the casing comprising a bottom 2 having the side wall 3 secured thereto and the end walls 4, "said side and end walls being of an equal height. Hinged as at 5 50 to the side wall 3 is the cover 6 and carried by the side wall is the bracket 7 comprising the tubular body 8 having the set screw 9 extending therethrough. This tubular body is held on the walls 8 by means of the flanges 55 10, which are riveted or otherwise secured

thereto as at 11. A curved reflector plate 12 is supported within the casing and extends from the forward front corner of the casing in an arcuate path so as to engage the rear wall 3 and the opposite front corner 60 as clearly shown in Fig. 1. The opposite ends of the reflector plate 12 are bent inwardly toward one another to provide flanges 12', the purpose of which will be hereinafter more fully described. Formed 65 at the front edges of the bottom 2, and the end walls 4, are the flanges 13, the use of which will appear as the description proceeds. The cover 6 is formed with a suitable flange 14, which cooperates with the 70 flanges 13 in supporting the slides in which the numbers are retained. A suitable connecting bar 15 connects the upper ends of the flanges as clearly shown in Figs. 2 and 3 of the drawings.

75 A rectangular frame 15' is positioned within the casing and is arranged to abut the inner side of the connecting bar 15 and flange 13. Secured to the upper and lower bars of the rectangular frame 15' are relatively spaced trough-shaped bars 16, the walls of which are provided at their free ends with outwardly extending flanges 17. These flanges 17 form retainers for the slides 18, which carry the numbers or letters designated by the numeral 19. A suitable glass plate or panel 20 is arranged between the flanges 17 of the bars 16 and the inturned flanges 12' of the reflector 12. The flanges 17 and frame 15' define pockets between the 80 walls of the bars 16 for permitting of the insertion of a plurality of the number plates or slides 18 therein. The plate or panel is so disposed as to permit the numbers on the plates or slides 18 to be read either in the 85 dark or light.

90 In order to illuminate the casing after dark, there is provided in the central portion of the bottom wall, a suitable lamp socket 21, in which the lamp bulb 22 is 100 mounted. It is to be understood however that any other suitable lighting device may be provided which will illuminate the interior of the casing so that the letters may be seen after dark.

105 It will be apparent from the foregoing that in use the device is attached to the rear end of the vehicle in place of the ordinary tail light and the proper characters 19 are then slipped in place, so that the proper 110

number or combination of numbers may be given.

While in the foregoing there has been shown and described the preferred embodiment of this invention, it is to be understood that such changes may be made in the combination and arrangement of parts as will fall within the spirit and scope of the appended claim.

10 What is claimed is:—

A device of the class described comprising a casing having a bottom wall, side walls, and end walls forming an open side, a transversely extending flange formed on the forward edge of the bottom wall, a hinged cover for said casing, a connecting bar secured by its opposite ends to the upper edges of the end walls, and extending transversely across the open side of the casing, a rectangular frame arranged in said casing and abutting the inner side of the flange and connecting bar, a plurality of trough-shaped retaining members secured to the upper and lower bars of the frame, said 25 retaining members spaced apart, and the

opposite walls of said trough-shaped members being bent outwardly to form flanges, a curved reflector plate extending from one corner of the casing back to the rear of the casing and to the opposite forward corner thereof, said reflector plate having its opposite ends bent inwardly toward one another to provide flanges, a transparent plate arranged between the flanges of the trough-shaped members and the flanges of the reflector, said frame and flanges of the trough-shaped members defining pockets between the side walls of the trough-shaped members, a plurality of interchangeable number plates or slides fitted in the pockets formed by the trough-shaped members and transparent plate, and means in the casing in the rear of the plate to illuminate the slides or plates.

In testimony whereof I affix my signature 45
in presence of two witnesses.

JAMES T. LISONBEE.
